VERNER LINDSJO, OF HOPEDALE, AND LEONARD M. ROGERS, OF MENDON, MASSACHUSETTS, ASSIGNORS TO DRAPER CORPORATION, OF HOPEDALE, MASSACHUSETTS, A CORPORATION OF MAINE

STOPPING MECHANISM FOR LOOMS

Application filed October 15, 1931. Serial No. 569,016.

This invention relates to shuttle changing looms and is more particularly directed to mechanism for stopping loom operation should either one of two loom parts be disturbed from their normal weaving position.

Shuttle changing looms are of two general types, one of which effects a change in the shuttles by arresting the loom operation and the other of which effects a change in the shuttles during the continued operation of the loom. The present invention is of the latter type and is associated with a shuttle changing loom which continues in operation during the change of shuttles.

It is now the ordinary practice to effect a change in the shuttles by the substitution for a shuttle in which the filling has become either broken or substantially exhausted, by a shuttle containing a fresh supply of filling. In effecting the shuttle change box plates of the change shuttle box are displaced from their normal position to permit the exit of the depleted shuttle and the entrance of a shuttle supplied with filling. Such displacement of the box plates may be variously effected, but it will happen at times that one or the other of the box plates will fail to return to normal weaving position after shuttle change, with the result that if the shuttle is picked from the change box under such conditions it is liable to be thrown through the warp threads, or get caught in the shed, or thrown out of the loom entirely and probably to the injury of the loom attendant.

During the loom operation should the shuttle get caught in the shed or "trapped" the warp threads are liable to be injured during the beat-up movement of the lay.

One of the important features of the present invention consists in a loom stopping mechanism which shall be rendered effective to stop the loom in case either of the defective conditions stated takes place. In carrying this feature of the invention into practical effect the box plates of the change shuttle box or one of them is connected to a stop initiating mechanism and a loose reed is associated with another initiating mechanism to effect loom stoppage in case the shuttle gets trapped in the shed. Associated with

each of the stop initiating mechanisms is a stop motion common to each, so that on the occurrence of either of the defective conditions noted, the common stop motion will be rendered effective to stop the loom.

The invention and novel features thereof will best be made clear from the following description and accompanying drawings of one good form thereof.

In the drawings:

Fig. 1 is a front to rear sectional elevation showing the loom parts in normal weaving position;

Fig. 2 is a similar sectional elevation showing the position of loom parts when a box plate fails to return to weaving position after a change of shuttles;

Fig. 3 is a similar sectional elevation showing the position of parts should the shuttle get trapped in the shed; and

Fig. 4 is a perspective view at the rear of the lay, some of the parts being shown in section and others broken away for clearness of illustration.

The loom frame 1 may be of usual construction for support of the operating parts. The lay 2 is carried by the usual lay sword 3 and has movement towards and from the front of the loom, as usual, by the pitman 4.

The change shuttle box at one end of the lay comprises a back plate 5 carried by arms 6 pivotally mounted at 7 on brackets 8 secured to the front of the lay. The front box plate 9 is carried by arms 10 mounted at 11 at the back of the lay. The back box plate 5 is normally under the impulse of a spring 12, normally acting to move the back box plate to weaving position after a change of shuttles. The front box plate 9 has an inclined portion 13 and is normally held in its lower weaving position by an abutment or screw 14 carried by one or more of the arms 6 of the back box plate, the effect being that when the back box plate is raised by any appropriate mechanism the front box plate is free to be lifted by the entering shuttle, or as more fully explained in applicant's co-pending application Ser. No. 523,455, filed March 18, 1931.

Secured to the arms of the back box plate

is a downwardly extending tail piece 15 which, on call for replenishment of filling, may be moved by an arm 16 extending from a shaft 17 supported on the loom frame and to which is connected a downwardly extending 5 arm 18 having a rearwardly extending operating member 19 which, on call for replenishment of filling, may be engaged by a bunter 20 on the lay, with the result that upon a shuttle change the back box plate will be lifted to permit the exit of the depleted shuttle and the incoming shuttle will itself lift the front box plate 9 as the full shuttle is moved rearwardly into the shuttle box. It 10 is not deemed necessary herein to enlarge upon the details of the mechanism for displacing the box plates for the change of shuttles, as the details of such mechanism form no essential part of the present invention and 15 are more fully and clearly described in the copending application above noted.

As hereinbefore stated, one at least of the box plates is associated with a stop initiating mechanism which, as shown in the present invention, consists of a shaft 21 supported by the lay for rocking movement and projecting from the shaft 21 is an arm 22 connected by a link 23 to the back box plate 5, the construction being such that when the 25 back box plate is raised to permit the change of shuttles the shaft 21 will be rocked.

Secured to the rock shaft 21 at the opposite side of the loom from the changed shuttle box, as indicated in Fig. 4, is a pull finger 24, which together with the shaft 21 and its 30 connection with the back box plate constitutes one of the stop initiating mechanisms.

Extending longitudinally of the lay is the reed 25, the upper end portion of which at 35 is mounted in the hand rail 27, for swinging movement, and concentric with the shaft 21 is a sleeve 28 mounted in suitable bearings 29 carried by the lay. Secured to the sleeve 28 and extending upwardly therefrom are 40 the arms 30 to which is secured a reed locking bar 31, Fig. 4, which is adapted to rest against the lower bar 32 of the reed and maintain it yieldingly in weaving position under the impulse of a spring 33, one end of 45 which may be fixed to the bearing 29 and the other end of which may be secured to an adjustable member 34 secured to the sleeve.

The sleeve 28 has secured thereto a dagger 50, Fig. 4, which under normal action of the spring 33 will be held in its lowered or inoperative position. The dagger 35 together with the sleeve and parts described relative thereto, constitute the second stop initiating mechanism.

Secured to and extending frontwardly 55 from the sleeve 28 is a locking finger 36 which, as the lay beats up, is adapted to engage beneath a fixed lug 37 secured to the loom frame, the construction being such that after the shuttle has been picked the reed

25 will be held yieldingly in its operative weaving position by the spring controlled member 28, and arms 30, so that should a shuttle get trapped in the shed or not complete its picking movement, the reed is free 70 yieldingly to move backwardly, but should the shuttle not get trapped in the shed as the lay beats up the part 36 will engage beneath the lug 37 and lock the reed for the beat up movement, as indicated more clearly in 75 Fig. 1.

As hereinbefore stated, the two stop initiating mechanisms are associated with a common stop mechanism to effect loom stoppage on backward movement of the lay should the 80 back box plate not return to normal weaving position after a change of shuttles, and effect loom stoppage on the frontward movement of the lay should the shuttle get trapped in the shed.

The stop mechanism common to both initiating mechanisms comprises a stop member 38 mounted on the loom frame for movement in two directions, and as shown is constituted as a stop rod mounted in bearings 39 for longitudinal movement towards and from the front of the loom. Adjustably mounted on the stop rod 38 is a lug 40 adapted to be engaged by the bunter 35 when the latter is operatively positioned on frontward movement of the lay. Likewise, adjustably secured to the stop rod 38 is a second lug 41 adapted to be engaged on backward movement of the lay by the pull finger 24, the lug 42 of which will engage frontward of the lug 41 on backward movement of the lay should the back box plate 5 fail to return to weaving position after a change of shuttles.

As exemplifying the operative conditions above described it will be noted that in Fig. 2 the pull finger 24 is engaged with the lug 41 to move the stop rod 38 rearwardly as the lay goes back, when the back box plate has failed to return to normal weaving position after change of shuttles. Likewise in Fig. 3 the position of parts, as indicated, shows the engagement of the lug 40 by the bunter 35 to move the stop rod frontwardly should the shuttle be trapped in the shed as the lay moves towards the front of the loom.

In addition to the stop rod 38 the loom stopping mechanism common to both stop initiating mechanisms includes a shipper 43 pivotally mounted on the loom frame at 44 and having a downwardly extending portion 45 which is provided with a projection 46, the construction being such that should a rearward force be applied to the shipper 43 above its pivotal mounting 44, the loom will be stopped and should a frontward impulse be imparted to the lug 46 carried by the shipper below its pivotal mounting the loom will again be stopped.

The stop rod 38 has pivotally connected thereto at 47 a shipper knock-off provided

with an upwardly extending arm 48 and a downwardly extending arm 49, the two arms extending to opposite sides of the path of movement of the stop rod. The upwardly extending arm 48 of the shipper knock-off has a shipper engaging portion 50, while the lower arm 49 has an end portion 51 bearing upon the projection 46 of the shipper below its pivotal mounting, the effect being that if the upper arm 48 of the shipper knock-off is moved rearwardly from the position indicated in Fig. 1, the loom will be stopped and if the lower end portion of the shipper is moved forwardly by the lower arm 49 of the shipper knock-off, the loom will again be stopped.

To effect these movements of the shipper knock-off a fixed fulcrum stop 52 is provided above the pivotal mounting of the shipper and a second fulcrum stop 53 is provided below the pivotal mounting of the shipper and when the parts are in normal weaving position, as indicated in Fig. 1, the upper and lower end portions of the shipper knock-off bear upon their fulcrum stops. Should the shipper rod 38 be moved rearwardly owing to the box plate not having returned to normal position, the shipper knock-off will turn around the lower fulcrum stop 53 and act upon the upper portion of the shipper to effect loom stoppage. Should the stop rod be moved forwardly from its normal position, as indicated in Fig. 1, the shipper knock-off will turn about the upper fulcrum stop 52, Fig. 3, thereby causing the lower end portion 51 of the shipper knock-off to act upon the lower end portion of the shipper and again turn the shipper to loom stopping position.

The shipper 43 has connected thereto the usual start rod and brake rod, the former being indicated by the rod 54 and the latter by the rod 55, both of which may be connected to the shipper by the projection 56.

From the construction described as one good practical form of the present invention, it will be noted that should a box plate not be returned to its normal position after the shuttle change, it will act through its initiating mechanism on the backward movement of the lay to actuate the loom stopping mechanism or throw the shipper to its idle position, and should the shuttle be trapped in the shed the initiating mechanism associated with the loose reed will again act through the same loom stopping mechanism to stop the loom or throw the shipper to its idle position.

When the shuttle becomes trapped in the shed and the dagger 35 is operatively positioned to effect loom stoppage, it may be desirable to retain or lock the dagger in such position with the reed displaced rearwardly and to this end the dagger 35 has pivotally connected thereto a locking member 57, which extends upwardly from the dagger through a loop 58 secured at the front of

the lay. In normal weaving operations, as indicated in Fig. 1, the locking member 57 is in its lowered position at which time a locking lug 59 is below the loop 58. When, however, the loom is stopped by reason of a trapped shuttle, the locking member 57 is raised to position the locking lug 59 above the loop 58, as indicated in Fig. 3, whereupon the arms 30 and locking bar 31 of the reed may be held in their reed releasing position. With the parts thus locked the shuttle may be readily removed from the shed whereupon the loom attendant may trip the locking member 57 through the hand piece 60 at the top of the locking member.

The hopper for the filled shuttles and the shuttle changing mechanism are not herein shown and described, because the details thereof form no part of the present invention and are fully and completely described in the copending application hereinbefore called to attention.

What is claimed is:—

1. In a loom of the shuttle changing type, the combination of the lay having a shuttle box provided with box plates adapted to be displaced from their normal weaving positions for the entrance and ejection of a shuttle, loom stop initiating devices operatively positioned to effect loom stoppage should one of the box plates fail to return to normal weaving position after a change of shuttles, a loose reed motion carried by the lay, loom stop initiating devices operatively positioned to effect loom stoppage should the shuttle be trapped in the shed, and a train of mechanism common to and actuated by either of the initiating devices for stopping the loom when the shuttle is trapped or the box plate fails to return to normal position.

2. In a shuttle changing loom, the combination of the lay, a reed mounted on the lay for rearward displacement by a trapped shuttle, a shuttle changing box having back and front box plates mounted for displacement from normal weaving position for change of shuttles, and a single train of loom stopping mechanism adapted to be actuated to effect loom stoppage when a shuttle gets trapped in the shed and also when one of the box plates fails to return to normal weaving position after a change of shuttles.

3. In a shuttle changing loom, the combination of the lay, a reed mounted on the lay for rearward displacement by a trapped shuttle, mechanism operatively positioned to effect loom stoppage by rearward displacement of the reed, a shuttle box having box plates at least one of which is mounted for displacement from normal weaving position for change of shuttles, mechanism operatively positioned to effect loom stoppage should one of the box plates fail to return to normal weaving position after a change of shuttles, and loom stopping devices common to both

said mechanisms for actuation by either to stop the loom.

4. In a shuttle changing loom, the combination of the lay, a reed mounted on the lay for rearward displacement by a trapped shuttle, mechanism operatively positioned to effect loom stoppage by rearward displacement of the reed, a shuttle box having box plates at least one of which is mounted for displacement from normal weaving position for change of shuttles, mechanism operatively positioned to effect loom stoppage should one of the box plates fail to return to normal weaving position after a change of shuttles, and loom stopping devices common to both said mechanisms for actuation by either to stop the loom including a stop member mounted for movement in one direction by one of said mechanisms and in another direction by the other of said mechanisms.

5. In a shuttle changing loom, the combination of the lay, a reed mounted on the lay for rearward displacement by a trapped shuttle, mechanism operatively positioned to effect loom stoppage by rearward displacement of the reed, a shuttle box having box plates at least one of which is mounted for displacement from normal weaving position for change of shuttles, mechanism operatively positioned to effect loom stoppage should one of the box plates fail to return to normal weaving position after a change of shuttles, and loom stopping devices common to both said mechanisms for actuation by either to stop the loom including a stop member mounted for movement in one direction by one of said mechanisms and in the opposite direction by the other of said mechanisms, and a shipper mounted for movement in one direction by either movement of the stop member.

6. In a shuttle changing loom, the combination of the lay, a reed mounted on the lay for rearward displacement by a trapped shuttle, mechanism including a dagger operatively positioned by rearward displacement of the reed, a shuttle box having a box plate mounted for displacement for change of shuttles, mechanism including a finger operatively connected to the box plate, a stop rod common to both mechanisms and having a bunter for engagement by the operatively positioned dagger to stop the loom on forward movement of the lay, a lug connected to the stop rod for engagement by the operatively positioned finger to stop the loom on rearward movement of the lay following change of shuttles and failure of the box plate to return to normal weaving position, and a shipper actuated by stop rod movement in either direction.

7. In a shuttle changing loom, the combination of the lay, a reed mounted on the lay for rearward displacement by a trapped shuttle, mechanism including a dagger oper-

atively positioned by rearward displacement of the reed, a shuttle box having a box plate mounted for displacement for change of shuttles, mechanism including a finger operatively connected to the box plate, a stop rod common to both mechanisms and having a bunter for engagement by the operatively positioned dagger to stop the loom on forward movement of the lay, a lug connected to the stop rod for engagement by the operatively positioned finger to stop the loom on rearward movement of the lay following change of shuttles and failure of the box plate to return to normal weaving position, a shipper and a knock-off member interposed between the stop rod and shipper.

8. In a shuttle changing loom, the combination of the lay, a reed mounted on the lay for displacement by a trapped shuttle, a shuttle box having a box plate mounted for displacement for change of shuttles, devices carried by the lay and controlled by the reed, devices carried by the lay and controlled by the position of the box plate, and stop mechanism common to the two devices and rendered effective to stop the loom when the reed is displaced and when the box plate fails to return to normal weaving position following a change of shuttles.

9. In a shuttle changing loom, the combination of the lay, a reed mounted for displacement by a trapped shuttle, a shuttle box having a box plate mounted for displacement for change of shuttles, two concentric rocking members mounted on the lay, one controlled in its rocking movement by the reed and the other controlled in its rocking movement by the box plate, devices on each rocking member to effect loom stoppage, a shipper, and means between the shipper and said devices and common to each of them to knock off the shipper when a shuttle is trapped in the shed or the box plate fails to return to normal weaving position after a change of shuttles.

10. In a stop motion for looms, the combination of a stop rod mounted for longitudinal movement, a shipper movable to and from loom running position, a shipper knock-off member mounted on the stop rod and having two parts engageable with the shipper, a fixed stop engageable with one end portion of the knock-off member to cause the said member to move about the fixed stop as the stop rod is moved in one direction to stop the loom, and a projection connected to the shipper and engaged by the knock-off member to cause the said member to move about another fixed stop to throw the shipper as the stop rod is moved in the opposite direction.

11. In a stop mechanism for looms, the combination of a stop member movable in either of two directions to effect loom stoppage, a shipper movable to and from loom running

position, a knock-off member connected to the stop member for swinging movement relative thereto, a fulcrum stop at each side of the path of movement of the stop member about one of which the knock-off member may turn as a fulcrum when the stop member is moved in one direction to effect loom stoppage and about the other of which the knock-off member may turn as a fulcrum when the stop member is moved in the opposite direction to effect loom stoppage.

12. In a stop mechanism for looms, the combination of a stop rod mounted for longitudinal movement in opposite directions from normal position to effect loom stoppage, a shipper pivotally mounted for movement to and from loom running position, a shipper knock-off pivotally connected to the stop rod and extending to opposite sides of the path of stop rod movement, a fulcrum stop for the shipper knock-off at opposite sides of the path of stop rod movement about one of which the shipper knock-off may turn as a fulcrum when the stop rod is moved from its normal position in one direction to stop the loom and about the other of which the shipper knock-off may turn as a fulcrum when the stop rod is moved from normal position in the opposite direction to stop the loom.

13. In a stop mechanism for looms, the combination of a stop rod mounted for movement in opposite directions from normal position to effect loom stoppage, a shipper pivotally mounted for movement to and from loom running position, a shipper knock-off pivotally mounted on the stop rod and having oppositely extending arms for engagement with the shipper at opposite sides of its pivotal mounting, a fulcrum stop for the shipper knock-off at opposite sides of its pivotal connection with the stop rod and about one of which the shipper knock-off may turn as a fulcrum upon movement of the stop rod in one direction from normal position to effect loom stoppage and about the other of which the shipper knock-off may turn as a fulcrum upon movement of the stop rod from normal position in the opposite direction to effect loom stoppage.

14. In a stop mechanism for looms, the combination of a stop rod mounted for movement in opposite directions from normal position to effect loom stoppage, a shipper pivotally mounted for movement to and from loom running position and having a projection below its pivotal mounting, a shipper knock-off connected to the stop rod for swinging movement in either direction and having an upper portion for knocking-off the shipper when the shipper knock-off is swung in one direction and a lower portion for knocking-off the shipper when the shipper knock-off is swung in the opposite direction, and fulcrum stops for determining the direction of swinging movement of the shipper knock-off

as the stop rod is moved from its normal position.

In testimony whereof, we have signed our names to this specification.

VERNER LINDSJO.
LEONARD M. ROGERS.
